UNITED STATES PATENT OFFICE.

ARTHUR BATES, OF LEICESTER, ENGLAND, ASSIGNOR TO UNITED SHOE MACHINERY COMPANY, OF PATERSON, NEW JERSEY, A CORPORATION OF NEW JERSEY.

COVER-SUPPORT FOR ABRADING OR POLISHING TOOLS.

1,119,000.

Specification of Letters Patent.

Patented Dec. 1, 1914.

Application filed March 29, 1912. Serial No. 687,038.

To all whom it may concern:

Be it known that I, ARTHUR BATES, a subject of the King of England, residing at Leicester, Leicestershire, England, have 5 invented certain Improvements in Cover-Supports for Abrading or Polishing Tools, of which the following description, in connection with the accompanying drawings, is a specification, like reference characters on 10 the drawings indicating like parts in the several figures.

This invention relates to abrading or polishing tools that have a renewable cover and is illustrated in connection with a buffering 15 roll cover.

Scouring or buffering rolls usually comprise an inner spindle to support the roll, a core of some light material to give the requisite diameter and an abrasive cover which is 20 wrapped around the core. It has been found that in operation centrifugal action expands the cover so that it fits somewhat loosely on the core and consequently there is a great tendency when work is applied 25 for the cover to creep and become cracked and thereby destroyed. Further, on certain classes of work a flexible and not a solid core is desirable.

It is an object of the present invention to 30 obtain a core which shall be flexible; shall run truly and be in balance; shall be sufficiently expansible to insure that the bellying of the abrasive cover under centrifugal action is accompanied by a corresponding 35 increase in the diameter of the core; shall afford a practically complete support for the whole of the abrasive cover at all times; and shall be cheap to produce. Accordingly in a buffering or like roll having a core and 40 an outer flexible abrasive cover there is provided between the core and the cover a cover support or bed comprising a strip of leather or like material which is adapted to encircle the core and the exterior part of which 45 is slashed or slit at an angle to its surface to produce a series of overlapping tongues or leaves which yieldingly support the cover when the roll is rotated.

It has been found in buffering certain parts 50 (for example the bottoms) of boots and shoes that it is of advantage to have two scouring rolls one carrying coarse abrasive material, such as sandpaper, on a relatively firm support and the other carrying fine

abrasive material on a flexible support; the 55 first roll is used for removing the bulk of the material and the second roll for giving the finish. It is found that when the roll comprises leather slashed to produce a series of overlapping tongues or leaves only 60 one roll need be used, for by pressing the work firmly upon the roll the tongues or leaves are forced inward to form at that point a practically solid core so that considerable material is removed from the 65 work; on the other hand, when the work is to be finished, it is pressed lightly upon the roll whereupon the extended tongues form a flexible core so that only a small amount of material is removed and a smooth 70 finish is given to the work.

In a convenient construction the cover support is in the form of a leather strip of rhomboidal outline which is so narrow that it can be wound spirally around the core 75 and which is cut into a series of tongues lying across the strip, the cuts preferably extending across the strip in a direction inclined obliquely in relation to the side of the strip, which inclination can be varied ac- 80 cording to requirements.

The leather instead of being cut into wide tongues may have a series of cuts or slits extending across the strip at an angle to the side of the strip and an additional series of 85 cuts extending at a similar inclination but in the opposite direction, the two series of cuts crossing and thus forming a series of narrow tongues which give a greater flexibility to the roll. When the roll is rotated these 90 tongues are forced out equally toward or into a radial position by centrifugal force and therefore tend to keep the abrasive material stretched evenly along its surface, while at the same time permitting it to yield 95 according to the pressure with which the work is pressed against the roll.

The flexible bed or cushion has been described as being of leather, but it is obvious that any other suitable material might be 100 used.

These and other features of the invention including certain details of construction and combinations of parts will be described in connection with an illustrative device and 105 pointed out in the appended claims.

In the drawings:—Figure 1 is a plan, partly in section, of a buffering roll in which

the present invention is embodied; Fig. 2 is an end elevation, partly in section, of the roll shown in Fig. 1, the arrow indicating the direction of rotation; Fig. 3 shows on 5 an exaggerated scale a portion of a cover support in the form of a leather strip slit so as to produce wide tongues; and Fig. 4 shows on a similar scale the result obtained by subjecting the piece of material shown in Fig. 10 3 to a second slitting operation whereby each of the wide tongues is cut into a plurality of narrow ones.

The roll chosen for illustration is of the type shown in Letters Patent to William 15 Gordon, No. 801,003, to which reference may be had for a more detailed description of its structure.

The roll comprises a wooden core 1 mounted in any suitable fashion upon the usual rotatable spindle 3. Immediately surrounding the wooden core there is provided a flexible leather support 5 around which the abrasive material 7, in this case sandpaper, is wrapped and upon which it is securely 25 clamped at either end of the roll by any usual or suitable clamping means, such for example as the fingers 9.

The leather in the present instance comprises a strip about one-quarter of an inch 30 thick and about an inch and three-quarters wide, said strip being in the illustrative roll of rhomboidal form. In order to prepare it for acting as a flexible bed for the sandpaper a series of slits or slashes are made across 35 the strip at any convenient angle, and these slits extend to within a small distance of the inner surface, the slits being at a suitable oblique angle to the surface of the leather. The slits are so close to each other that parallel sided tongues or leaves 11 of leather, about a thirty-second of an inch thick, are formed which are joined together at their bases by the uncut portion of the leather. The strip of leather is then wound spirally 40 around the core of the roll and secured thereto in any suitable manner.

When the roll is rotated at a very high speed the tongues by centrifugal action will tend to become radial and in so doing will 45 enlarge the circumference of the roll and thus support the sandpaper equally at all points. In the upper half of Fig. 2 the tongues are shown in the position which they occupy when the roll is at rest; and in the lower half, in the position which they occupy during rotation of the roll. It is found that the sandpaper so supported responds very sensitively to the pressure of the work upon it and that its contact surface 50 readily conforms to the varying contours of the surface of the work being operated upon. Further, it is found that by varying the pressure of the work against the roll, a variety of results may be obtained. For instance, if the work is gently pressed against

the roll a velvety finish is produced, whereas if more pressure is exerted the tongues of leather are closed up to form a more solid support with resultant changes in the quantity of material removed and in the surface 70 produced on the work.

It is obvious that the leather may be made flexible by cutting in a number of ways. In Fig. 4, for example, the slits or slashes cross one another, the result of this treatment 75 being that the wide tongues shown in Fig. 3 are each cut up into a series of narrower ones which upon rotation of the roll tend to fly out into radial position, thus producing a somewhat more even surface than is obtained when the slits are all parallel to one another.

A roll with a flexible bed for the abrasive material constructed in accordance with the present invention will more readily give the 85 required finish to the work than the rolls at present in use, and it has been ascertained that by using a medium coarseness of abrasive material one roll constituted in accordance with the present invention may be used 90 in place of the two older type rolls carrying coarse and fine abrasive material respectively. In such case the work is at first pressed firmly against the roll so that the 95 surface of the latter becomes firm and hard and afterward it is pressed lightly against the roll so that the entire surface of the abrasive material may be resiliently supported by the extended tongues.

Although the invention has been set forth 100 in connection with a buffing tool of particular construction, it should be understood that the invention is not limited in the scope of its application to a tool of the construction described.

Having thus described my invention, what I claim as new and desire to secure by Letters Patent of the United States is:

1. An abrading or polishing tool having a core and a flexible cover in combination with a cover support comprising a sheet of leather provided with slits arranged close together and extending at an angle oblique to its surface.

2. An abrading or polishing tool having a core and a flexible cover in combination with a cover support located between said cover and core comprising a sheet of flexible material, having a plurality of overlapping tongues integral therewith, said tongues extending obliquely to the periphery of said roll when said roll is at rest.

3. An abrading or polishing tool having a core and a flexible cover in combination with a cover support located between said cover and core comprising a sheet of flexible material provided with slits inclined to its edge and extending obliquely to its surface.

4. An abrading roll having in combination a core, a cover support wrapped about

said core, said support consisting of a sheet of leather having a plurality of slits forming thin contiguous tongues extending obliquely from said sheet, a cover of sand-paper wrapped tightly about said support, and clamping means at each end of said roll for holding said cover in place.

In testimony whereof I have signed my name to this specification in the presence of two subscribing witnesses.

ARTHUR BATES.
